UNITED STATES PATENT OFFICE.

REUBEN RICHARDSON, OF HUNTSVILLE, OHIO.

CHAIR.

SPECIFICATION forming part of Letters Patent No. 272,901, dated February 27, 1883.

Application filed February 3, 1882. (Model.)

To all whom it may concern:

Be it known that I, REUBEN RICHARDSON, of Huntsville, in the county of Logan and State of Ohio, have invented certain new and useful Improvements in Chairs; and I do hereby declare the following to be a full, clear, and exact description of the invention, such as will enable others skilled in the art to which it pertains to make and use the same.

10 My invention relates to chairs, and more particularly to that class of chairs which are adapted to be revolved upon a supporting-standard, whereby they may be turned under a desk or to one side, out of the way, when not required for use.

15 The invention consists in the improved construction and combinations of parts hereinafter fully described, whereby the chair-seat is supported by a loop-bearing, the latter being pivotally connected to a stepped standard, thus firmly bracing the chair and permitting its being turned under a desk when not in use.

20 In the drawings, Figure 1 is an isometric view of a chair constructed in accordance with my invention, in connection with a desk-platform and desk, the chair being in position to be used. Fig. 2 shows a sectional view with the chair turned under the desk. Fig. 3 is a perspective view of the loop-bearing and chair-pivot detached, and Fig. 4 is a similar view of the supporting-standard.

25 A represents a post or standard, secured to an enlarged base, B, the latter being perforated, and adapted to be secured by screws b to the floor or desk-platform C, and internally screw-threaded to receive the screw-threaded end a of the post.

30 D represents a desk. The standard is preferably so arranged relative to the desk that a line drawn from the inner edge of the top of the desk to the floor C would pass centrally through the standard. Thus the standard will be out of the way when the chair is turned as shown in Fig. 2. A slight variance from this 40 location of the standard, however, may be made, if desired. The standard is formed with a step, a', near its base and a second step or bearing, a'', near its upper end, a³, which latter is pointed to receive the looped bearing of the 45 chair.

E represents the chair-seat, which may be of any desired construction. To its under side is secured, by screws e or other means, a metallic or other disk, F. Depending or projecting from the center of the latter is the chair-pivot G, of tapering form.

H represents the chair bearing or brace, consisting of a strip of metal looped or bent upon itself to form the supports h h'. The latter are parallel with each other for a short distance from the bend, and each provided with a perforation or pivot-bearing, i, the latter being in the same vertical plane to receive the pivot G of the chair. The lower brace, h', of the bearing H then extends forward and downward at an incline, and terminates in a horizontal bend, h², which is provided with a perforation; h³, of a size to allow the brace h² to be slipped over the upper portion of the standard A and rest upon the lower step, a'. The upper brace, h, of the bearing H then extends horizontally forward to the front of the chair-seat, where it is bent slightly downward and forward, as shown at i', and provided with perforations i², adapted to fit over the upper end, a³, of the standard and allow the brace to rest on the step a² of said standard. It will be apparent that when the chair is thus secured it may be freely revolved both on the pivot G and around the standard A, and readily removed when desired. The looped strip affords a firm and secure bearing for the chair, as it forms both a horizontal and diagonal brace for the latter; and by the construction of the standard with the upper and lower steps or 85 bearings and pointed upper end the perforated strip H may be readily removed.

90 The several parts of my improved chair are all of simple construction and may be manufactured at a small cost.

Many slight changes in the details of construction might be resorted to without departing from the spirit of my invention, and hence I do not limit myself to the precise construction shown in the drawings, but reserve the 95 right to make such alterations in form as may properly fall within the scope of my invention.

Having fully described my invention, what I claim as new, and desire to secure by Letters Patent, is—

The combination, with the chair-base B and standard A, the latter constructed with the upper and lower step-bearings, a^2 a' , and the loop-brace H, having its upper arm journaled at its end on the upper step-bearing, a^2 , and its lower and diagonal arm journaled at its end on the lower step-bearing, a' , of the seat E, provided with a pivot, G, that is inserted through both the upper and lower arms of the

brace, and thereby furnished with an extended bearing therein, substantially as set forth.

In testimony whereof I have signed this specification in the presence of two subscribing witnesses.

REUBEN RICHARDSON.
